UNITED STATES PATENT OFFICE.

EBEN C. CROCKER, OF SANDUSKY, OHIO, ASSIGNOR TO HORACE A. MOSES, OF MITTINEAGUE, MASSACHUSETTS.

REFINING-ENGINE.

No. 834,718.

Specification of Letters Patent.

Patented Oct. 30, 1906.

Application filed February 26, 1906. Serial No. 302,916.

To all whom it may concern:

Be it known that I, EBEN C. CROCKER, a citizen of the United States, residing at Sandusky, county of Erie, and State of Ohio, have invented certain new and useful Improvements in Refining-Engines, fully described and represented in the following specification and the accompanying drawings, forming a part of the same.

This invention relates to improvements in driving mechanism of paper-refining engines, the engines for which the improvements have been particularly designed being engines of the "Jordan" type. This type of engine includes generally a stationary shell within which a cutting core or plug is rotatably mounted. The cutting-knives of this plug wear down after some time, and this type of engine is now provided with adjusting mechanism by which the plug may be given an endwise or longitudinal movement relatively to the shell to adjust the cutting-surface of the plug to the shell, this relative adjustment compensating for the wear of the plug-knives. It has been proposed to drive this cutting core or plug directly from an electric motor, the shaft of the motor and plug-shaft being arranged in substantially axial alignment and coupled together, several important advantages resulting from such arrangement. It has also been proposed to movably mount the electric motor, so that the electric motor can be moved with the core or plug as the latter is moved by the adjusting mechanism. A very considerable strain is thrown on the parts of the mechanism by this movement of the motor, and as now constructed this strain is borne by the coupling member or clutch connecting the motor and the plug-shaft and by the adjusting mechanism. I have discovered that the proper working of the adjusting mechanism may be insured and the life of the clutch or coupling prolonged by relieving the coupling and the adjusting mechanism of this strain by providing means independent of the plug and its shaft for adjusting or moving the motor endwise as the plug and its shaft are moved or adjusted endwise relatively to the shell, an embodiment of such means being shown in the accompanying drawings, in which—

Figure 1 is a side elevation of a paper-refining engine, showing the improvement, cer-

tain parts being broken away. Fig. 2 is a 55 partial end view of the driving-motor and connections looking in the direction of arrow 2 in Fig. 1. Fig. 3 is an end view, looking in the direction of arrow 3 in Fig. 1, of certain gearing employed in the mechanism for adjusting the motor or moving it endwise as the plug and its shaft are so adjusted or moved.

In the drawings, which illustrate one embodiment of the invention, 1 indicates a base, which base may be of any usual or desired construction, but which is preferably so constructed as to support both the refining-engine 2 and its driving-motor 3, such construction being convenient. The refining-engine shown is of the Jordan type and comprises an outer stationary shell 4, supported in any suitable manner, as by standards 5, rising from the base 1, and a cutting core or plug 6, mounted to rotate within the shell. This cutting core or plug 6 is mounted on a 75 shaft 7, journaled in bearings 8 on standards 9, rising from the base 1. The plug and the plug-shaft are held normally against endwise or longitudinal movement relatively to the shell 6. As the machine is used, however, 80 the knives of the core or plug wear down, and an adjustment of the core relatively to the shell is necessary in order that the knives on the cutting-surface of the core or plug may properly operate with the shell in refining the stock. Means are provided, therefore, for both normally holding the plug and plug-shaft against endwise or longitudinal movement relatively to the shell and for giving such movement to the plug and its shaft 90 relatively to the shell to effect this adjustment, which means include a wheel and screw device, such as shown at 10.

The plug-shaft 7 and the plug 6 are driven by an electric motor, such a motor being 95 shown at 3. This driving-motor is supported so as to be movable endwise or longitudinally relatively to the base 1 and is mounted on the base in any suitable manner to afford such movement. In the construction shown 100 that part of the base which supports the motor is provided with projections or raised portions 11, one of these raised portions being provided on each side of the base 1. These raised portions extend upwardly above 105 the plane of the base proper and form tracks on which the motor is movably supported. The motor is slidably retained on these

tracks by plates 12, suitably secured to the tracks, these plates being engaged by flanges 13 on the motor-frame 14. The motor has a shaft 15 rigidly secured on the motor-armature 16, which shaft is, as shown, in substantially axial alinement with the plug-shaft 7 and is connected with the plug-shaft by the clutch or coupling member 17.

It will be seen that if in the construction 10 so far described when the motor is moved or adjusted endwise such movement is given it by the adjusting mechanism through the plug-shaft and the coupling member connecting the motor-shaft and the plug-shaft 15 the strain of the movement will come on the coupling, plug-shaft, and the adjusting mechanism for the latter. The means provided by the present invention for so moving the motor, and thus relieving the coupling 20 member, plug-shaft, and the adjusting mechanism for the latter of this strain, will now be described. These means may be varied, but will include an adjusting device acting directly on the frame of the motor and 25 cooperating with the adjusting mechanism for the core, so that the movement given the motor by this device will be equal to that given the plug by the adjusting mechanism.

In the specific embodiment of the invention shown there is provided a shaft 18, which shaft extends the length of the machine and is suitably supported in bearings 19 on the base 1. This shaft has a threaded end 20, which works in a nut 21, suitably secured to the motor-frame 14, preferably centrally on its lowermost portion, as shown. The other end of this shaft 18 carries a gear 22, which gear meshes with a gear 23. This gear 23 is an intermediate gear and is supported in any suitable manner, as by a short shaft 24, mounted in a bracket 25, secured on the standard 9. This intermediate gear meshes with a gear 26, which is mounted on the screw-shaft 27 of the adjusting device 10. 45 By this construction when the plug is moved endwise by the screw-shaft 27 of the adjusting mechanism the motor is also given an endwise movement by the shaft 18, which with its connections act directly on the motor-frame, thus relieving the coupling of strain. In order that the movement given the motor by the shaft 17 shall be equal to the movement given the plug by the adjusting mechanism, the screw-shaft 27 and the shaft 18 55 are provided with threads of equal pitch and the gears 22 and 26 made equal gears. With this construction the motor and the plug are moved endwise at the same time and the same distance.

60 What is claimed is—

1. In a refining-engine, the combination with a stationary shell, of a cutting core or plug rotatably mounted within the shell, a plug-shaft on which the plug is supported, 65 adjusting mechanism for adjusting the plug

and its shaft endwise relatively to the shell, an electric driving-motor for driving the plug-shaft and adjustably mounted in axial alinement therewith, and means independent of the plug and shaft for adjusting the motor 70 endwise as the plug and shaft are adjusted.

2. In a refining-engine, the combination with a stationary shell, of a cutting core or plug rotatably mounted within the shell, a plug-shaft on which the plug is supported, 75 adjusting mechanism for adjusting the plug and its shaft endwise relatively to the shell, an electric driving-motor for driving the plug-shaft and adjustably mounted in axial alinement therewith, and means acting directly 80 on the frame of the motor and independent of the plug and its shaft, for adjusting the motor endwise as the plug and shaft are adjusted.

3. In a refining-engine, the combination 85 with a stationary shell, of a cutting core or plug rotatably mounted within the shell, a plug-shaft on which the plug is supported an electric driving-motor adjustably mounted in axial alinement with and driving the plug-shaft, means acting directly on the motor-frame for adjusting the motor, adjusting mechanism for adjusting the plug-shaft endwise relatively to the shell, and connections 90 between said adjusting mechanism and the adjusting means whereby the plug and motor are simultaneously adjusted.

4. In a refining-engine, the combination with a stationary shell, of a cutting core or plug rotatably mounted within the shell, a 100 plug-shaft on which the plug is supported, adjusting mechanism for adjusting the plug-shaft endwise relatively to the shell, an electric motor adjustably mounted in axial alinement with and driving the plug-shaft, means 105 acting directly on the motor-frame for adjusting the motor, said means including a shaft threaded to the motor-frame, and connections between the shaft and said adjusting mechanism for rotating the shaft whereby the plug and the motor are simultaneously 110 adjusted.

5. In a refining-engine, the combination with a stationary shell, of a cutting core or 115 plug-shaft on which the plug is supported, adjusting mechanism for adjusting the plug and its shaft endwise relatively to the shell, a driving means for the plug-shaft mounted adjustably in axial alinement therewith, and means independent of the plug and shaft for adjusting the driving means endwise as the plug and shaft are adjusted.

In testimony whereof I have hereunto set my hand in the presence of two subscribing 125 witnesses.

EBEN C. CROCKER.
